UNITED STATES PATENT OFFICE.

OSCAR L. GERWIG, OF CANTON, OHIO.

BRICK RE-PRESS.

SPECIFICATION forming part of Letters Patent No. 761,826, dated June 7, 1904.

Application filed February 10, 1904. Serial No. 192,887. (No model.)

To all whom it may concern:

Be it known that I, OSCAR L. GERWIG, a citizen of the United States, residing at Canton, in the county of Stark and State of Ohio, have invented a new and useful Brick Re-Press, of which the following is a specification.

The invention relates to a machine for repressing bricks or other articles which have been approximately shaped and partly 10 pressed; and the object of the improvement is to provide a simpler mechanism than has heretofore been used to effectively perform all the movements and work necessary in such a re-press. This object is attained by the construction, mechanism, and arrangement illustrated 15 in the accompanying drawings, in which—

Figure 1 is a front elevation of the re-press, showing the plungers down; Fig. 2, a side elevation showing the plungers raised; Fig. 3, a 20 vertical section on line 3 3, Fig. 1; Fig. 4, a similar section, showing the plungers raised; and Fig. 5, a cross-section on line 5 5, Figs. 1 and 3, showing details of the upper cross-head and guide.

25 Similar numerals refer to similar parts throughout the drawings.

A double machine—that is, one having two dies and two sets of plungers—is used to illustrate the invention, and in the frame 1 are 30 provided the cross-girders 2 and 2^a, on which the double die 3 is mounted, which die is of the usual form, with the matrices 4 comprising through vertical apertures, each having such a cross-section as it is desired to finally 35 form the bricks.

The vertical guides 5 and 6 are provided on the inner sides of the frame-standards, in which guides the slides 7 and 8, respectively, on the ends of the upper and lower cross-heads 9 and 40 10 are adapted to operate. The upper and lower plungers 11 and 12 are formed or attached on the respective cross-heads and are adapted to enter and operate in the matrices of the die in the usual manner.

45 The rock-shaft 13 is mounted crosswise in the frame directly above the middle line of the die, and on this shaft is hung the pendent shaft 14 by the adjustable pendulum-rods 15, preferably located at the ends of the shaft. The 50 eccentric 16 is mounted on the main shaft 17,

preferably located in the same plane as the lowest position of the pendent shaft, and the free end of the eccentric arm 18 is journaled on the pendent shaft, preferably at the middle thereof, and motion is imparted to the main 55 shaft by the gear 19, the counter-shaft 20, and the pulley 21.

The long connecting-rods 22 are journaled on the pendent shaft above and to the lower cross-head below and are located to pass freely 60 on each side of the die and the upper plungers, for which purpose the upper plungers are placed on the forward extension 23 on the body of the upper cross-head, and the short and preferably adjustable connecting-rods 24 65 are journaled on the pendent shaft above and to the forward extensions of the upper cross-head below, by which arrangement the cross-heads and the plungers thereon are adapted to be raised and lowered by the swing- 70 ing of the pendent shaft to and from its lowest position, and the difference in the lengths of the connecting-rods results in a corresponding difference in the rate and extent of the vertical movements or strokes of the respective 75 plungers.

The various parts of the mechanism are so located, arranged, and proportioned that when the lower plungers are elevated in the matrices to or near the upper side of the die by a 80 movement of the pendent shaft from its lowest position, which is the proper place for these plungers for receiving the approximately-formed and partly-pressed bricks and for discharging the re-pressed bricks, the upper plungers are likewise elevated far enough above the lower ones to freely receive the bricks between them, as shown in Fig. 4, and when the lower plungers are permitted to drop down in the matrices to or near the lower side of 85 the die by the movement of the pendent shaft to its lowest position the upper plungers are depressed by the same movement of the pendent shaft to enter part way into the matrices, thereby re-pressing the bricks, as shown in 90 Figs. 1 and 3, the compression of the bricks being accomplished by the approach of the upper plungers toward the lower ones resulting from the different rates of their depression. The depth of the die is preferably pro- 100

portioned with reference to the depth of the bricks and the amount of vertical compression to be made in them, so that the work of compression will begin at the same time the upper plungers enter the matrices.

It will be noted that the rock-shaft and pendulum-rods are only used for sustaining and raising and lowering the compressing mechanism and that the real work of the re-press is done by bringing the pendent shaft in line with the two plungers, whereby the plungers are forced together, the long connecting-rods being in tension and the short ones in compression. For this reason the particular means illustrated and described for sustaining and laterally moving the pendent shaft are not essential parts of the more particular feature of the invention, which is the method of operating the plungers; but it is preferred to use the rock-shaft support, because the movement given thereby to the pendent shaft is well adapted to raise and lower the compressing mechanism at the proper time with reference to the coming together of the plungers.

What I claim as my invention, and desire to secure by Letters Patent, is—

1. A re-press comprising a frame having vertical guides and a die having a vertical matrix, cross-heads above and below the die having slides adapted to operate in the guides and

plungers adapted to operate in the matrix, a rock-shaft above the die having a shaft depending therefrom, connecting-rods of different lengths journaled on the pendent shaft and to the respective cross-heads, and means for 35 swinging the pendent shaft.

2. A die having a vertical matrix, vertically-movable plungers one above the other adapted to operate in the matrix, a pendulous shaft above the die, and connecting-rods of different 40 lengths journaled on the shaft and to the respective plungers.

3. A pair of vertically-movable plungers one above the other, a pendulous shaft above the plungers, and connecting-rods of different 45 lengths journaled on the shaft and to the respective plungers.

4. A pair of vertically-movable plungers one above the other, a laterally-movable shaft above the plungers, and connecting-rods of different 50 lengths journaled on the shaft and to the respective plungers.

In testimony whereof I have signed my name to this specification in the presence of two subscribing witnesses.

OSCAR L. GERWIG.
